(57) **CLAIM**

The ornamental design for a toy top spinner, as shown and described.

DESCRIPTION

FIG. 1 is an inverted front view of the toy top spinner showing my design;

FIG. 2 is an inverted rear view thereof;

FIG. 3 is a right side view thereof;

FIG. 4 is a left side view thereof;

FIG. 5 is a top view thereof;

FIG. 6 is a bottom view thereof;

FIG. 7 is a top and front perspective view thereof;

FIG. 8 is a top and rear perspective view thereof; and,

FIG. 9 is a bottom and rear perspective view showing the design as it appears with its cord extended and with an associated top and toy scoring device attached thereto.

The broken lines showing the top and scoring device are included for the purpose of illustrating environmental structure that forms no part of the claimed design. The remaining broken lines are included for the purpose of illustrating portions of the toy top spinner that form no part of the claimed design.

1 Claim, 5 Drawing Sheets
